UNITED STATES PATENT OFFICE

139,414

DESIGN FOR A SUN GOGGLE OR THE LIKE

Bernard Ulvad, Leominster, Mass., assignor to
Fosgood Corporation, Leominster, Mass., a cor-
poration of Massachusetts

Application August 12, 1944, Serial No. 114,873

Term of patent 14 years

(Cl. D57—1)

To all whom it may concern:

Be it known that I, Bernard Ulvad, a citizen of the United States, residing at Leominster, in the county of Worcester, State of Massachusetts, have invented a new, original, and ornamental Design for a Sun Goggle or the like, of which the following is a specification, reference being had to the accompanying drawing, forming part thereof, in which:

Figure 1 is a front view of a sun goggle or the like embodying the design;

Fig. 2 is a top plan view; and

Fig. 3 is a side view thereof.

The temples are shown fragmentarily in Figs. 2 and 3 for convenience of illustration.

My design for a sun goggle is characterized by the configuration of the front of the frame with beveling applied thereto in a manner as illustrated, in combination with the particular shape of the lens openings and the convexedly curved interchangeable lenses which have axes of symmetry all as shown.

I claim:

The ornamental design for a sun goggle or the like, substantially as shown and described.

BERNARD ULVAD.
